UNITED STATES PATENT OFFICE.

THOMAS JAMES WASSER, OF JERSEY CITY, NEW JERSEY.

RAIL-LIFT.

No. 880,344.

Specification of Letters Patent.

Patented Feb. 25, 1908.

Application filed June 12, 1906. Serial No. 321,349.

To all whom it may concern:

Be it known that I, THOMAS JAMES WAS-
SER, a citizen of the United States, and a
resident of Jersey City, in the county of Hud-
5 son and State of New Jersey, have invented
certain new and useful Improvements in Rail-
Lifts, of which the following is a specifica-
tion.

This invention relates to means for secur-
10 ing a continuous line of rail between the ter-
minals of different lengths thereof.

Its organization comprises a rail lift which
with its appurtenances, forms a continuous
line of rail for a wheel at the ends of a pair of
15 rails.

The invention in the accompanying draw-
ings is shown with the approach and draw-
of a bridge.

Figure 1 represents a plan view of the rail
20 lift and its appurtenances, Fig. 2 shows a
section of Fig. 1 on the line 2, 2, Fig. 3 is a
right hand end view of Fig. 1, Fig. 4 is a sec-
tion of Fig. 1 on the line 4, 4, Fig. 5 represents
a section of Fig. 1 on the line 5, 5, Fig. 6
25 shows a section of Fig. 1 on the line 6, 6, Fig.
7 represents a section of Fig. 1 on the line 7,
7, Fig. 8 is a section of Fig. 1 on the line 8, 8,
Fig. 9 represents a bottom plan view of Fig.
1, and Fig. 10 shows a plan view of a pair of
30 rail lifts with their accompanying rails, ap-
plied to the approach and draw of a bridge.

A rail lift 20 is shown with the upper longi-
tudinal flat portion 21 of the tread of a wheel
to roll on, and a longitudinal groove or de-
35 pression 22 for the flange of a wheel. Near
the swinging end 23 of the lift the flat portion
21 is narrowed as shown at 24, and at the
other end both sides of the lift are narrowed
40 as shown at 26 and 27. The end beyond
the portion 26 terminates in the narrow por-
tion 28.

The lift is supported in the stationary
frames 30 and 31. The said frames extend
45 upwardly at their sides and ends to the level
of the face of the flat portion 21 of the rail
lift. They are separated as shown at 32 to
give the required clearance. There are
50 formed at 33 and 34 flat surfaces for the face
of the tread of the wheel beyond the portions
24 and 26 of the lift. At 35 and 36 there is
left sufficient clearance between the lift and
the frame to allow for variations due to ex-
55 pansion and contraction, and sufficient clear-
ance is also allowed at 25 and 43. The con-
tour of the edges between the frame 31 and
the lift 20 at 25 and 43 are arcs of circles,

described from the axial center of the pin 8,
and by means of this construction the clear-
ance at these points is always the same, ob-
viating any great gap when the lift is either 60
up or down.

The frame 30 has formed therein a depres-
sion or pocket 44 to support the end of the
rail lift, and a depression or pocket 37 in the
frame 31 also constitutes a support for the 65
said lift. In the latter frame is formed an
opening 38 for the end 28, and a journal pin
39 supported in the frame 31 carries the right
hand end of said lift and allows it to swing.
In the opening 38 below the lift is journaled 70
the bent lever 40 on the pin 41. The end of
said lever carries the roller 42 which can be
made to bear against the bottom face of the
lift. The journaled end 28 of the lift fits
closely at its sides and end to the frame 31, 75.
so as to form as little clearance as possible.
The frame 30 beyond the line 50 is made to
conform to the ordinary section of the rail
used, and the frame 31 beyond the line 51 is
made to conform to the same section. The 80
ends of the frames are beveled or mitered as
shown at 52 and 53. Lugs 54, 55 extend
from the frame 30, and lugs 56, 57 and 58
extend from the frame 31.

To use the invention the parts are assem-
bled as shown in the drawings, the frames
being secured in place by means of the lugs.
Sufficient clearance is especially taken at 35
and 36 to allow for expansion and contrac-
tion. 90

When a wheel rolls over the frames and
lift, and supposing it to be rolling in the di-
rection of the arrow, and after the wheel
leaves the narrow end 53 and bears on the
portion 34 of the frame, it also bears on the 95
narrow portion 26 of the lift, and at the joint
25 is supported by the narrow portion 27,
preventing jar. While the wheel is passing
the joint 25 it is supported on the flat por-
tion 34 of the frame 31. When the tread of 100
the wheel passes the joint 36 it is supported
on the flat portion 21 of the lift and the edge
of the frame 30, and when the wheel passes
the joint 35 it is supported on the flat portion
33 of the frame 30. It will be evident that 105
during the passage of the wheel over any of
the joints, a flat bearing is at all times pre-
sented for the tread of the wheel.

Having described my invention, I claim:
1. The combination in a rail lift having a 110
longitudinal flat upper surface and the ends
thereof narrowed, a frame surrounding the

lift and the lift hinged to the frame, the upper edge of the frame being on the same level with the flat upper surface of the lift.

2. The combination in a rail lift of a pair of frames surrounding said lift, a pin joining the lift with one of the frames, a pocket formed in one of the frames for supporting the swinging end of the lift, the upper edges of the frame being on the same level with the upper surface of the lift.

3. The combination in a rail lift of a pair of frames surrounding said lift, and the upper edges of the frames on a level with the upper surface of the lift, a pin joining one end of the lift and one of the frames, a pocket formed in one of the frames for supporting the swinging end of the lift, a lever fulcrumed in one of the frames and arranged to bear against the lift to raise the same.

4. The combination in a rail lift having a longitudinal flat upper surface and a longitudinal depression adjacent to said surface, the ends of the lift being narrowed, a pair of frames surrounding said lift with their upper surfaces on a level with the upper flat surface of the lift, a pin joining one end of the lift with one of the frames, pockets formed in the frames for supporting the swinging end of the lift, a lever fulcrumed in the frame under the lift, a roller journaled in the lever and arranged to bear up against the lift.

5. The combination in a rail lift having a longitudinal flat surface, frames surrounding the lift, a pin in one of the frames to form a

hinge between the lift and said frame, joints between the lift and one of the frames formed with arcs described from the axial line of the said pin, and the upper edges of the frame on the same level with the flat upper surface of the lift.

6. The combination in a rail lift having a longitudinal flat upper surface, of a frame with means for supporting said lift, the frame having miter ends, the upper edges of the frame on the same level with the said flat surface, and a pin in the frame for joining the lift therewith.

7. The combination in a rail lift of a pair of frames surrounding said lift, the upper edges of the frames on a level with the upper surface of the lift, the ends of the frames narrowed and having miter edges, a pin joining one end of the lift and one of the frames, joints between the lift and frame formed with arcs described from the axial line of the pin, a pocket formed in one of the frames for supporting the swinging end of the lift, a lever fulcrumed in one of the frames and arranged to bear against the lift to raise the same.

Signed at Jersey City in the county of Hudson and State of New Jersey this 1st day of June A. D. 1906.

THOMAS JAMES WASSER.
